UNITED STATES PATENT OFFICE.

JOHN M. McCALAIN, OF SPOKANE, WASHINGTON.

BED-BOTTOM.

1,321,119.

Specification of Letters Patent.

Patented Nov. 11, 1919.

Application filed October 21, 1918, Serial No. 259,121. Renewed August 9, 1919. Serial No. 316,491.

To all whom it may concern:

Be it known that I, JOHN M. McCALAIN, a citizen of the United States, residing at Spokane, in the county of Spokane and 5 State of Washington, have invented certain new and useful Improvements in Bed-Bottoms, of which the following is a specification.

The present invention relates to improvements in bed bottoms, particularly of the 10 slat and spring type, and the bed bottom which is the subject matter of the invention is designed particularly with the view of providing a comparatively inexpensive, but 15 effective, resilient, and durable support of this type which is well adapted for the required flexibility, yet in possession of sufficient rigidity to support the weight required without sagging or without undue depression. 20

The invention consists essentially in certain novel combinations and arrangements involving the parallel, longitudinal slats and their supporting cords or cables, and particularly in the manner of combining these 25 slats and cords with the bottom frame.

In the accompanying drawings one complete example of the physical embodiment of the invention is illustrated, combined and 30 arranged according to the best mode so far devised for the practical application of the principles of the invention.

Figure 1 is a top plan view of a bed bottom of the slat and spring type embodying 35 the novel features of the present invention.

Fig. 2 is a longitudinal sectional view at line A—A of Fig. 1.

Fig. 3 is an enlarged view of one of the 40 slats, showing also the independent and individual cable or wire for suspending each slat.

Fig. 4 is an enlarged transverse sectional view of one of the end bars of the bottom frame, showing details of construction.

45 In carrying out the principles of the invention and physically embodying the same in actual practice, a rectangular frame of suitable size is utilized, composed essentially of the two end bars 1 and 2 and the side bars 3 and 4, all preferably of properly prepared wood, and the two end bars which might be termed the head and foot bars of the frame, are each provided with beveled

or inclined upper faces 5, 5, to eliminate sharp corners or edges and to allow for required movement of the supporting or suspending members of the bed bottom, while at 6, 6, the outer curved faces of these bars are grooved, for a purpose to be described. 55

The supporting medium of the bed bottom 60 consists in a series of parallel slats 7, longitudinally arranged with relation to the bed, and preferably of wood of proper thickness, or thinness, to render them somewhat resilient to provide a flexible bottom. Each slat is 65 independently and individually supported between the two end bars through the medium of a cable or wire 8, which at 9, 9, is looped or bent about the end bars and passed loosely through the eyes or staples 10, 10 in 70 the bottom of the slat. Each slat has two loops 9 at each end, and beneath each slat the cables or wires are stretched along each side of the slat between the eyes or staples so that the slat is stable and presents a well 75 sustained and supported element in the series of parallel members. The supporting wires or cables pass loosely through the eyes of the staples so that the slats may be adjusted, longitudinally of the bed, and the 80 ends of each cable are joined by a coiled spring as 11. Each cable is thus capable of movement throughout its length, and to prevent wear by the loops 9 around the curved faces of the end bars, friction rods, of 85 metal, as 12, 12 are retained in the grooves 6, before referred to, to take up wear and prevent the wires or cables cutting into the wood from wear.

Preferably the slats in the series are 90 joined or bound together by a pair of wires 13, which binding cords or wires are woven about the slats, to retain them loosely, but at the same time prevent displacement. The inclined faces 5 on the end bars, it will be 95 apparent, permit depression of the upper strands of the supporting cables or wires without undesirable contact with a sharp corner or edge, thus allowing for sufficient depression of the wire and at the same time 100 providing a somewhat broad supporting face for the wire, in addition to the flat horizontal top surface of the end bars.

Claim—

105 The combination with a supporting frame including the end bars having inwardly and

downwardly beveled upper faces and friction members at their outer faces, of a series of parallel slats loosely woven together and provided with staples at their under faces, 5 supporting wires for each slat, each said wire having end loops about the end bars and frictionally engaging the friction mem-

bers, a spring connecting the ends of each wire, and said wires passed loosely through the staples to permit relative movement between the slat and wire. 10

In testimony whereof I affix my signature.

JOHN M. McCALAIN.
